UNITED STATES PATENT OFFICE.

MICHAEL CLINTON, OF PHILADELPHIA, PENNSYLVANIA, ASSIGNOR OF ONE-FOURTH TO PENN PRINTING HOUSE, ONE-FOURTH TO HARRY MILLER, OF DELAWARE COUNTY, AND ONE-FOURTH TO WILLIAM E. CUNNINGHAM, OF PHILADELPHIA, PENNSYLVANIA.

ART OF DISCHARGING SHEETS FROM A PRINTING-PRESS SUBSTANTIALLY FREE FROM ELECTRICITY.

1,216,211.

Specification of Letters Patent. Patented Feb. 13, 1917.

Application filed January 27, 1915. Serial No. 4,969.

To all whom it may concern:

Be it known that I, MICHAEL CLINTON, a citizen of the United States, residing at Philadelphia, in the county of Philadelphia and State of Pennsylvania, have invented 5 certain new and useful Improvements in the Art of Discharging Sheets from a Printing-Press Substantially Free from Electricity, of which the following is a specification.

When the printed sheets are discharged from a printing press, they, very frequently, are charged with static electricity. This charge is generally insignificant upon a single sheet, but, when the charged sheets are piled on each other, they become unmanageable. The sheets deposited by the press slide sidewise instead of lying straight, the pile is hard to part and individual sheets 15 cannot be withdrawn, and many other obstacles are offered to easy and regular printing. This charge of electricity can be and is acquired in various ways; sometimes it appears to arise from friction, either in the 20 rapid passage of the sheets through the air, or their withdrawal from the unprinted stack of paper; sometimes the stack of papers seems to have been charged before it is put on the press. Sometimes the paper 25 seems to have been charged by induction while on the roller by electricity generated in the press by its revolution.

My method of discharging the charge of static electricity from the paper passing 30 through a printing press, comprises heating the paper, while passing through press, by bringing it into contact with a heated conductor of electricity, which is grounded electrically and comes substantially into electrical 35 contact with the whole of the surface of the paper. The heating of the paper causes the electricity to pass freely from the paper to the conductor, whence it is carried by the grounding to the earth. The reason 40 that heating increases greatly the deelectrifying effect of the conductor, is because the moisture, always present in the paper, is evaporated, filling the air immediately in contact with the paper with moisture, so that 45 the electricity lying on the points of the surface of the paper that do not actually touch the conductor, will be opposed by

much less resistance in reaching the heated conductor. As the static electricity collected on a sheet of non-conducting material such 55 as paper, remains nearly fixed at one location and does not flow along the surface, the advantage of having a medium between the grounded conductor and the paper that will offer the least resistance at the points 60 where the surface of the paper and the heated and grounded conductor are minutely out of contact with each other, is obvious, and the effect in substantially totally freeing 65 the paper from electricity readily conceived. This condition applies more particularly to winter, when the air can contain little moisture, even inside an ordinarily heated building; in summer when the moisture is plentiful little if any static electricity 70 is collected by the sheets.

The best way of which I am aware of carrying out the art above mentioned, and an apparatus I find in practice suitable for this purpose I will now describe.

75

In the drawings, Figure 1 is a side elevation of part of a press, and Fig. 2 is a front elevation of part of a press, each figure showing an apparatus suitable for carrying out the art above described in what I regard as the best way.

The paper is carried from the pack into the press in any usual way. The paper, while passing through the press, is heated to a temperature of say 100° Fahrenheit. 85 The paper is heated on both sides, by heating the cylinder 3, upon which the paper is carried, and also heating the side of the paper away from the cylinder. I have found the best way to do this is by passing 90 the paper between the pipe 4 and the cylinder 3. I heat the pipe 4 to a high temperature usually approaching 200° Fahrenheit. This pipe will heat the bed of the cylinder through the paper, and, in case 95 the passage through the press of the paper is intermittent, it will heat the cylinder directly while the paper is not passing. I make the pipe 4 of a conducting material and allow it to come into electrical contact 100 with the paper so as to conduct off any electricity that has been produced upon the sheets previously. For this purpose I connect the pipe 4 electrically with the earth.

2
The pipe 4 is grounded by means of the conductor 8. The paper is heated, on its exposed side by the pipe 4. This heating raises the moisture from the paper into the air immediately around the pipe, so that the electricity passes from every point in the surface of the paper to the pipe.

I claim—

10 The art of removing static electricity from sheets of paper which consists in passing the sheets in contact with an electrically grounded conductor heated to a heat exceeding summer heat, and bringing substan-

tially the entire surface of the sheet into contact with the conductor; whereby the 15 moisture produced in the air in immediate contact with the paper and the conductor, lessens greatly the resistance to the passage of the electricity from points on the paper minutely separated from the conductor. 20

In testimony whereof I hereunto affix my signature in presence of two witnesses.

MICHAEL CLINTON.
